UNITED STATES PATENT OFFICE.

HORACE PLUMMER, OF LAWRENCE TOWNSHIP, MARION COUNTY, INDIANA.

ENGRAVING BLOCK.

Application filed October 31, 1924. Serial No. 747,006.

This invention relates to improved holding means whereby articles may be held or carried in various positions to be worked upon by engravers or others, the invention 5 having reference more particularly to an apparatus adapted for holding jewelry or other articles either stationarily or movably and under control of an engraver or other artisan.

10 An object of the invention is to provide a generally improved engraving block which shall be of such construction as to be adapted to hold articles conveniently and securely to be engraved or otherwise worked upon, 15 especially various articles of different sizes and shapes, and without requiring a cumbersome lot of detachable devices requiring tiresome care-taking.

Another object is to provide an engraving 20 block of the above-mentioned character which shall be of such construction as to securely hold articles either stationarily or movably and permit of either free rotary movement or slow retarded movement, and 25 which shall be readily adjustable to the needs of the engraver.

A further object is to provide an adjustable engraving block which shall have a removable table to securely carry an article 30 and shall be adapted to be secured in a small lathe chuck to permit the article to be worked upon in a lathe.

A still further object is to provide improvements in various parts and also provide 35 new advantageous parts or features in engraving blocks, to the end that important advantages shall be obtained by the engraver, jeweler or other artisans working on small articles required to be held with precision.

With the above-mentioned and other objects in view, the invention consists in an engraving block having various novel features and improved parts affording improved facilities whereby a large variety of 45 articles may be securely held to be worked upon, particularly relating to reversibility and adjustability of various parts; and, the invention consists also further in various 50 novel parts and in the combinations and arrangements of parts as hereinafter particularly described and further defined in the claims appended hereto.

Referring to the drawings,—Figure 1 is a 55 top plan showing the major portion of the improved engraving block, partially broken

away to disclose improved internal features thereof; Fig. 2 is an enlarged fragmentary sectional elevation approximately on the plane of the line II—II in Fig. 1; Fig. 3 is 60 an elevation of the engraving block, minus a number of the removable parts thereof; Fig. 4 is a sectional elevation of the engraving block, as on the line II—II, in which different applications of removable parts 65 are seen; Fig. 5 is a side view of one of the adjustable and permissibly removable parts of the apparatus; Fig. 6 is a sectional elevation approximately on the line VI—VI in Fig. 1, in which a number of removable 70 parts are omitted; Fig. 7 is a side view of one of the removable parts of the apparatus, on an enlarged scale; Fig. 8 is a fragmentary elevation partially in section on the line VIII—VIII on Fig. 1; Fig. 9 is a top 75 plan of one of the improved vise jaw heads on an enlarged scale; Fig. 10 is a horizontal section of the jaw head, as on the line X—X in Fig. 15; Fig. 11 is an elevation of one of the improved holding studs or pins comprised in the invention, being on an enlarged scale; Fig. 12 is a sectional elevation of the improved stud; Fig. 13 is an end view of a half-nut type of a controlling head 80 embraced in the apparatus; Fig. 14 is a side 85 elevation of Fig. 9; Fig. 15 is a section on the line XV—XV on Fig. 9; Fig. 16 is a section on the line XVI—XVI on Fig. 9; and Fig. 17 is a fragmentary elevation in 90 which parts shown in Fig. 3 are inverted to effect adjustability.

In the various figures of the drawings similar reference characters indicate corresponding elements or features of construction referred to hereinafter in detail.

A preferable embodiment of the invention comprises a foundation part which is adapted to be supported upon a work bench or table whether or not the surface thereof is a true plane, and preferably the foundation is composed mainly of thick leather comprising a vertical annular wall 1 having a metallic stiffening liner 2 therein, the top of the wall having an inwardly extending annular ledge 3 integral therewith. The bottom of the wall being slightly yielding to unevenness of bench surface permits the wall to rest firmly in place. A heavy metallic base 4 is provided which has a spherical bottom portion 5 and a flat top 6, the bottom portion being adapted to adjustably rest on the ledge 3 and permit noiseless tilting 100 105 110

movement of the base on its foundation, the base being hemispherical and having an axial bore 7 therein and also a screw threaded hole 8 extending from the curved bottom portion to the bore, a set-screw 9 being arranged in the hole to securely fasten a bearing case 10 which is closely but removably fitted into the bore. The case 10 has a central bore 11 and a screw-threaded hole 12 extending through the wall of the case to the bore in which a set-screw 13 is fitted, a plurality of the set-screws being preferred. The case has also a ball cup or race 14 at one end of the central bore and a ball cup or race 15 in the opposite end of the bore. Adjacent to the periphery of the base a socket 16 is accurately drilled from the flat face 6 to receive a lock screw or pin. The case 10 can be adjusted longitudinally in its bore or may 20 be arranged in relatively inverted position, permitting the base to be inverted and to rest very solidly on its flat face 6.

An improved heavy metallic table or bed plate 17 is provided which has flat lower and upper faces, and the table is provided with an axle that has a head portion 18 rigidly secured centrally to the lower portion of the table, the axle having a body portion 19 extending through the bore 11 and provided 30 with a conical bearing portion 20 that is supported upon bearing balls 21 arranged in the cup 14. A conical collar 22 is screwed onto the end of the axle, so as to be adjustable thereon, and is guided by bearing balls 23 arranged in the cup or race 15. A locking screw 24 is screwed into the collar 22 to lock it to the axle and preferably has a centering point 25 adapted to be seated in the center cavity left in the end of the axle 40 after having been turned in a lathe, so that the locking screw acts as a brace to steady the bearing cone 22 in its position on the axle. Ordinarily the axle is not engaged by the set-screw 13 but is free to rotate in the bearing case. The table has a vertical guide hole 26 adjacent to the edge thereof that may be brought into alignment with the socket 16, and the upper portion of the hole has screw threads 27 therein. A locking pin 50 28 is fitted into the hole 26 and has screw threads 29 on its upper portion that are fitted to the threads 27, the portion of the pin 28 at the lower end of the threads thereon being stopped against the threads in the hole to prevent the pin from being moved upward obstructively beyond the top face of the table. The lower end of the pin 28 has a pointed portion 30 adapted to guide the pin into the socket 16, and the upper end of 60 the pin has a screw driver slot 31 therein whereby the pin screw may be turned in the pin hole.

The upper portion of the table has a guideway 32 that is coextensive with the diameter of the table and has a groove con-

stituting a shaft bearing 33 centrally in the bottom thereof, the bearing being half-round and coextensive with the remainder of the guideway. The guideway is formed partially by parallel guide bars 34 and 35 composed of upper portions of the table with a slot space between them. An improved operating and controlling shaft 36 is provided that is approximately as long as the guideway and it has two collars 37 and 38 thereon spaced apart on opposite ends of the middle portion of the shaft. The shaft has reversely pitched screw threads 39 and 40 that are directly supported in the shaft bearing groove to rotatably guide the shaft. For 80 precisely maintaining the operating shaft in position for correct operation the table has two aligning bores 41 and 42 therein extending from the periphery of the table to the guideway at right angles to the latter, 85 and two cylindrical plugs 43 and 44 are inserted in the bores respectively, the inner ends of the plugs having forks 45 and 46 respectively that are closely fitted between the collars 37 and 38 on opposite ends of 90 the shaft, the forks together closely embracing the shaft. The outer ends of the plugs are flush with the periphery of the table and have screw driver slots 47 and 48 therein respectively, whereby to correctly bring the 95 forks to proper position when inserting the plugs which are very closely fitted into the bores and are secured in place by means of set-screws 49 and 50 arranged in the under side of the table and engaging the plugs respectively. The plugs may be adjusted by slightly moving them inwards to compensate for wear in connection with the shaft. The shaft 36 is provided with an improved removable crank for rapid operation, and to this end the shaft 36 has a bore 51 extending from each end thereof and a screw driver slot 52 in the end of the shaft. The crank has a stem 53 removably arranged in the bore 51, one end of the stem having a head 54 thereon that has lugs 55 to be entered in the screw driver slot for rotating the shaft 36. The head has a crank arm 56 rigidly secured thereto. The opposite end of the stem 53 is adapted to be used as a screw driver to manipulate the various screws comprised in the apparatus.

Two improved controlling heads 57 and 58 are provided which are of the half-nut type adapted to slide in the guideway 32, and each has saddle-like contact with the upper portion of the shaft 36, the under portion of the head having screw thread portions 59 therein corresponding to and engaging the screw threads 39 and 40 respectively. The heads have central portions extending upward between the guide bars 34 and 35 and the tops of the heads have vertical cylindrical posts 60 and 61 rigidly connected thereto, respectively. Two liners 62 and 63

are arranged between the controlling heads and the guide bars 34 and 35 respectively and are provided with adjusting screws 64 and 65 respectively that are appropriately inserted in the guide bars respectively to force the liners to the controlling heads and compensate for wear.

For the purpose of excluding filings and other matter from the shaft 36 and other operating parts, a bridge plate 66 is secured at opposite ends thereof to the top of the table 17 above the plugs 43 and 44 and extends over the guideway 32 intermediately of its ends, the main portion of the plate being slightly higher than the top of the table, and two cover plates 67 and 68 to cooperate with the bridge plate are arranged to slide upon the top of the table and cover the remaining portions of the guideway and portions of the controlling heads that operate between the guide bars 34 and 35, the plates having apertures receiving the posts 60 and 61 respectively whereby the plates are moved, and permitting ready removal of the plates to oil parts beneath, the inner ends of the plates extending under the bridge plate 66 to continuously cover the guideway.

Two improved metallic jaw bodies 69 and 70 are provided which are preferably cylindrical, and each body has a socket bore 71 in its lower portion, the bodies being interchangeable on the posts 60 and 61, the posts being received into the socket bores respectively and rotatably supporting the bodies with the top of the posts in contact with the bottom of the socket bore. Each jaw body has a set-screw 72 in one side thereof that may be forced into engagement with the adjacent post to prevent rotation of the jaw body when set as may be desired on the post. The upper portion of each jaw body has an upwardly facing shoulder 73 which preferably is formed by cutting away a portion of the side of the body to constitute a recess, the shoulder and the back 74 of the recess preferably being inclined, and the back of the recess above the shoulder has a similarly inclined tongue 75 thereon, the side edges of the tongue being under cut to constitute parallel dove tail connection portions.

A pair of improved similar jaw heads are provided that are adapted to be invertibly connected to the jaw bodies, the heads comprising body members 76 and 76', each having on one side a pair of guide ribs 77 and 78 adapted to slidably engage the sides of the tongue on the jaw body, the ribs extending from the body at an inclination towards one another and holding the body of the head in place as it rests upon the shoulder 73. Each jaw head body has a novel head portion 79 thereon in which are a suitable number of socket bores 80 to receive holding studs or pins as may be required, and the

opposite ends of the head portion have slightly projecting lips 80 and 80' respectively that may be formed by under cutting the sides closely adjacent to the normal top of the head portion, whereby articles may be gripped when the pair of jaws are forced apart, said upper portions being curved to constitute segments of circles. Each head portion has also a suitable number of relatively smaller socket bores 82 that extend entirely through the head portion, and the middle of the front of the head portion preferably has a groove 83 therein to receive portions of articles when clamped between the jaws. Stud pins 84, 84', are provided which are arranged in the bores 82 and have each a slot 85 in its lower portion, permitting diametrical expansion of the pin so as to frictionally hold the pin tightly in the bore. The normal upper end of each pin has a small lip 86 thereon produced by cutting a groove in the pin adjacent to its top. When not in use the pins are pushed down so as to not project from the top of the head portion, but may be readily pushed up a suitable distance when required for use.

The jaw heads are provided also with removable and interchangeable holding studs or pins, some being characteristically different from others to afford a wide range of facilities, and one form of construction thereof comprises a stud body 87 having a novel head that extends over beyond one side of the body at an inclination and has a projecting acute angled lip 88, the opposite side of the head having an inclined face 89 and an acute angled projection 90 at the bottom of the face, the extreme top of the head having an acute angled lip 91 formed by under-cutting so as to leave a small supporting shoulder below the lip. The stud body has screw threads 92 thereon extending from the bottom end thereof. A sleeve 93 is arranged to slide over the body and has a flared upper portion to receive the head of the stud, the top of the flared portion being inclined to correspond approximately to the inclination of the face 89, constituting an adjustable rest member on which articles may be supported while being gripped by the lips or projections on the head. The body 94 has a longitudinal groove 95 to receive a spline, a nut 96 is arranged on the body against the sleeve 93 to operate in connection with the screw threads, and a spline 97 is arranged in the groove and extends through the nut, the spline having a lug 98 thereon that is anchored in the sleeve 93 and also a lug 99 engaging the lower side of the nut, so that the sleeve shall be moved with the nut. The stud has a base sleeve 100 screwed onto it and suitably secured against rotation, preferably by means of a lock pin 101, the base sleeve having a true smooth exterior adapted to be removably inserted into

either one of the sockets 80 to be firmly supported therein. Another form of holding stud or pin which in some cases is advantageously used in association with that above described, comprises a cylindrical body 102 adapted to be removably supported in one of the sockets 80, one side of the body having a concavity 103 adjacent to one end of the body whereby an acute angled lip 104 is provided, the opposite side of the body having a relatively shorter sharp lip 105 at the end of the stud and also another lip 106 adjacent thereto. Slightly farther away from the end of the stud one side thereof has a recess 107 to receive a portion of an article that may be gripped by the projections or lips 105 and 106 or either one of them. The body has also a relatively larger concavity 108 adjacent to the opposite end thereof, an acute angled lip 109 slightly back from the end of the stud, another gripping lip 110 at the extremity of the stud to grip an article that may be supported above the projection 109, the opposite side of the stud having another lip 111 formed by under-cutting so that the lip does not project beyond the side of the stud but may be entered into a socket 80.

Each jaw head body 76 and 76' has two wings 112 and 113 adjacent to the head portion 79, being on the side of the body opposite to that on which the ribs 77 and 78 are located, the wings converging each towards the other and between which a face block 114 is dove-tailed and held with its butt end against the head portion 79, the jaw head being inverted to make use of the face block, the latter being composed of wood or other suitable non-metallic substance not likely to mar articles that may be held between the two blocks.

In practical use the apparatus will be operated or manipulated somewhat similarly to well known engraving blocks, but more effectively and with great precision, and the artisan will readily make such changes in adjustments and change holding devices in the jaw heads as will be found to be most advantageous. In some cases the articles to be worked on are clamped between the gripping holding devices, in other cases the jaws are forced apart to securely hold articles. Face blocks 114 may be provided in variety and may be readily reshaped as varying needs may require. When tilting the base 4 on its foundation the movement is smooth and noiseless and the base is not liable to be moved accidentally. In some cases the bearing case 10 is withdrawn with the table from the base, the set-screws 13 are forced against the shaft body 19 to lock the case thereto, after which the case 10 may be secured in a lathe chuck to permit turning the articles that may be held by the jaws mounted on the table. At times it may be desired that the

table rotate freely on the base; at times it may be desired that the table be frictionally retarded to prevent too free movement, the table having slight frictional contact with the top of the base, as seen in Fig. 6, or the table may bear heavily upon the base so as to prevent accidental rotation of the table. When closely adjusting the table to the base by adjusting the case 10 in the base the table may be precisely raised or lowered by manipulation of the screw pin 26 on the top of the base with the screw 9 withdrawn, and when the proper adjustment has been made the screw 9 is to be forced against the case 10 to lock it in place. The screw pin should afterward be released from the base. The various features of construction and parts of the apparatus will suggest to the artisan many other uses thereof that will be found to be highly advantageous and economical. 85

What is claimed as new is:

1. An engraving block having jaw bodies and jaw heads removably connected to the upper portions of the jaw bodies respectively, the jaw heads being invertible on the jaw bodies and provided with holding devices adjacent to the tops and bottoms thereof, the bottom devices being different from the top devices. 90
2. An engraving block including a table, two cylindrical vise jaw bodies adjustably mounted vertically upon the table, and two jaw heads removably connected in inclined positions to the upper side portions of the jaw bodies respectively, each jaw head being invertible on the jaw body and having a plurality of holder sockets in the normally upper portion thereof. 100
3. An engraving block having vertical jaw bodies provided each with an inclined stop shoulder and an inclined dove-tail guide tongue above the shoulder, and jaw heads having each a pair of dove-tail guide ribs on its back to co-operate with the tongue, the head being invertibly supported upon the shoulder. 105
4. An engraving block including vise jaws with sockets therein, and grip devices comprising bodies having bases removably seated in the sockets respectively, each of the bodies being screw-threaded and having a nut to operate thereon, each device including a head inclined on the top of the body, and a supporting sleeve on the body connected to the nut and having a flared upper portion to embrace the under portion of the head. 110
5. An engraving block including a table, controlled heads adjustably supported in the table and having posts respectively, a pair of jaw bodies rotatively adjustable on the tops of the posts respectively and two jaw heads removably connected at an inclination to the jaw bodies respectively and invertible thereon, each jaw head having a plurality of 115

holding studs removably connected to one end thereof and also a non-metallic face block removably connected to the opposite end thereof.

- 5 6. An engraving block including a table, two controlled cylindrical posts adjustably supported by the table, two cylindrical jaw bodies having sockets in the lower portions thereof receiving the posts respectively, the 10 bottoms of the sockets having supporting contact with the tops of the posts and rotatably supporting the bodies, each jaw body having a holding tongue on the upper portion of one side thereof, and jaw heads 15 reversibly connected to the tongues on the bodies respectively, each jaw head having holder sockets in one end thereof and means adjacent to the opposite end thereof to secure a yielding face block thereto.
- 20 7. An engraving block including a table having a guideway therein, a portion of the guideway being open in the top of the table, a screw-threaded operating shaft rotatably supported directly on the bottom of 25 the guideway, a pair of controlling heads arranged in the guideway and connected with the operating shaft, each head having a post thereon, a bridge plate secured to the top of the table and extending over the guideway 30 intermediately of its ends, two cover plates connected to the posts respectively and extending across the remaining portions of the guideway and also under the bridge plate upon the table, and vice jaws mounted on 35 the posts respectively.

8. In an engraving block, the combination of a jaw body having a shoulder and a guide tongue on one side thereof, and a jaw head removably supported upon the shoulder 40 and having guide ribs on its back co-operating with the tongue to hold the head on the shoulder, said head having stud-sockets in one end and wings to hold a face block adjacent to the opposite end thereof, the head 45 being invertible on said shoulder.

9. In an engraving block, the combination of a base, a table rotatably mounted on the base and having a guideway therein extending to the top of the table, an operating

shaft guided in the guideway and having 50 reversely pitched screw threads, two controlling heads movable in the guideway and connected with the screw threads respectively, each head having a post thereon, two cover plates connected to and movable by the 55 posts respectively and covering each a portion of the guideway, and vice jaws mounted on the posts above the cover plates respectively.

10. In an engraving block, the combination 60 of a table having a guideway therein and two smooth bores at right angles to the guideway and extending to opposite sides of the guideway, an operating shaft rotatably supported in the guideway and having two collars spaced 65 apart and also reversely pitched screw threads extending away from the collars respectively, two plugs in said bores respectively and secured therein, the inner ends of the plugs having forks respectively that extend between the collars in guiding contact therewith, a pair of controlling heads arranged in said guideway and connected with said screw threads respectively, and vice jaws connected with the controlling heads re- 70 spectively.

11. In an engraving block, the combination, with a table and vise jaws on the table having sockets in the top thereof, of a plurality of studs comprising each a base sleeve 80 to be supported in a socket, a stud body secured in the base member and having screw threads thereon, said body being provided with a head that extends over beyond one side of the body at an inclination, the upper 85 end of the inclined portion having an acute angled lateral lip thereon, the head having an inclined top face and gripping lips at the top and the bottom of the inclined top face, and a supporting sleeve adjustable on 90 the stud body and having a flared upper portion to receive said head, the sleeve being provided with an adjusting nut connected with said screw threads.

In testimony whereof, I affix my signature 95 on the 27th day of October, 1924.

HORACE PLUMMER.
